PORTFOLIO LOCK

Karl August Franzen, Wald, Germany

Application May 9, 1932, Serial No. 610,197
In Germany May 23, 1931

2 Claims. (Cl. 70—2)

The object of the present invention is to provide portfolios and the like with simple closing means allowing the closing flap to be released and opened with one hand, and the invention consists broadly in connecting the lock to the closing flap instead of to the body of the portfolio and adapting it to serve as a hand grip for the manipulation of the flap, the lock being for this purpose arranged in a projecting position and fitted with a spring controlled latch element which can be operated by means of a press button.

Fig. 1 of the accompanying drawing represents a front view of a lock arrangement according to the invention,

Fig. 2 is a section on the line II—II of Fig. 1,

Fig. 3 is a section on the line III—III of Fig. 1, and

Fig. 4 is a view of the interior of the lock.

In said drawing *k* represents one of the side walls of a portfolio or the like, and *a* is the closing flap. A lock casing *b* is provided which in the illustrated arrangement projects beyond the edge of the flap and which is secured to the latter through the medium of a winged extension *c*. The casing *b* is connected to a backing plate *r* and has an aperture for the reception of a stud *h* connected, by means of a plate *i*, to the side wall *k*, and a latch plate *e* in the casing has a corresponding aperture *l* which also admits the stud. The latch plate is able to rock in its own plane about a nose piece *f* which is hooked to the edge of a flange *r'* on the plate *r* and it is controlled by a spring *g* under the influence of which it engages in a notch in the stud *h* so as to secure the flap in closing position. The spring *g* is arranged between the flange *r* and a lug *e'* on the latch plate. A press button *d*, which projects through one side wall of the casing *b*, can be used for rocking the plate *e* so as to release it from the stud. For this purpose the casing can be gripped between the thumb and a finger, the thumb being placed on the press button, and the

flap can thus be released and opened with one hand.

The press button *d* may either be integral with the plate *e* or provided with an extension *o* and connected by means of the latter to a flange *p* on the plate.

The flap can be locked by means of a key for which purpose a resilient locking member in the form of a U-shaped blade spring *m* is arranged to slide in an extension of the aperture *l* and adapted to be interposed between the stud *h* and the edge of the aperture *l* so as to prevent the plate from being rocked by means of the press button. The locking member *m* is moved into and out of locking position by the bit of a key which turns about a pin *n*.

One member of the spring *m* is bent to form a breast *m'* for engagement with the key bit when the latter moves downwards, and an inclined tail end *m''* for engagement with the bit when moving upwards.

I claim:

1. In a lock for a portfolio having a closing flap, a lock housing forming a rigid unitary structure secured in a projecting position to said flap and maintained in rigid relationship with the latter, a stud secured to the portfolio in position to enter an aperture in said lock housing, a spring-controlled latch member in the lock housing adapted to interlock with said stud, and a press button projecting from one side of the lock housing for operating the latch member.

2. A lock structure as claimed in claim 1 wherein the latch member consists of a plate having an aperture adapted to receive the stud and to allow the plate to move into and out of engagement with the latter, a resilient locking member slidably guided in said aperture and adapted in one position to bear against the stud and prevent the plate from moving, and means for supporting a key in position to operate said locking member.

KARL AUGUST FRANZEN.
